3 Claims. (Cl. 230—116)

1

This invention relates to gas and steam turbines, and particularly to the cooling of the turbine rotors.

The cooling of the highly stressed rotors of gas and steam turbines is of increased importance when it is desired to employ motive fluids of high temperatures, and the prior cooling methods have been open to various limitations and objections. It is known to blow a cooling agent upon the end surface of the rotor, and also to cool the inlet end of the cylindrical surface of the rotor by introducing a cooling layer of air or gas within the annular stream of motive gas. The cooling layer is thrown outwardly by centrifugal force and, except at the first row of blades, the cylindrical surface of the rotor is exposed to the full heat of the motive fluid.

These types of cooling have the drawback that the heat transfer radially of the rotor takes place by conduction through the metal of the rotor, but design requirements are frequently best satisfied by constructions which leave cylindrical or annular spaces within the rotor, and these spaces act per se as heat insulation. It has been proposed to improve the cooling in hollow rotors of reversing turbines by means of a liquid within the rotor. It was thought that the liquid would increase the rate of heat transfer along the cylindrical rotor wall, and that the inactive section of the turbine rotor would thereby cool the rotor section which was then in operation. It was found that the liquid within the rotor gave rise to vibration and noise. Water could not be employed as the cooling medium in view of its relatively low boiling point and mercury, although theoretically satisfactory as a heat transfer liquid, increased the vibration. Even if it were possible to find a liquid which would be reasonably satisfactory, this cooling system would still be open to the objection that centrifugal force holds the liquid against only those surfaces which are farthest from the axis of rotation. There is substantially no cooling of radial disks or partitions within a rotor, and these elements are the structural parts which are subjected to the highest mechanical stresses and which therefore require intensive cooling.

Objects of the present invention are to provide turbines in which the rotors are constructed with internal recesses, and which afford a more vigorous cooling of the cylindrical surfaces and of any radial disks than has been possible with prior turbines. Objects of the invention are to provide turbines and turbine-compressor assemblies having hollow rotors, and in which a high rate of cooling or heat transfer axially of the rotor is

2

effected without introducing a liquid heat-transfer medium into the hollow rotor. More specifically, an object is to provide turbines in which the rate of heat transfer between the parts of a rotor with internal recesses is increased by placing the air or gas within the recess or recesses under a heavy pressure. A further specific object is to increase the rate of heat transfer in turbine rotors by employing hydrogen under heavy pressure as the heat-transfer medium within the recess or recesses of the rotor.

These and other objects and the advantages of the invention will be apparent from the following specification when taken with the accompanying drawings in which:

Fig. 1 is a schematic view, in longitudinal section, of a hollow rotor for a high temperature turbine, the rows of blades being omitted.

Fig. 2 is a curve sheet showing the temperature gradient along a hollow rotor, curve I being for a rotor of the known type with a gas filling at atmospheric pressure, while curve II shows the temperature gradient when the rotor is charged with a gas under high pressure.

Fig. 3 is a longitudinal central section through a turbine embodying the invention, and in which the rotor includes a radial disk or partition which divides the hollow interior of the rotor into two cylindrical recesses or chambers, and

Fig. 4 is a longitudinal central section through the rotor of a turbine-compressor, the rotor being constructed in accordance with this invention to effect a cooling of the turbine section of the rotor by heat transfer to the compressor section thereof.

In Fig. 1 of the drawing, a hollow rotor body is illustrated somewhat schematically as comprising end disks *a* and *b* connected by a cylindrical wall *c*, the disks being secured to shafts *s* which support the rotor body in suitable bearings not shown. It is assumed that the highly heated motive fluid flows from right to left along the cylindrical rotor surface *c* and the blades, not shown, and establishes a maximum temperature *T* at the right-hand end of the cylindrical wall *c*.

The end disk *a* is cooled in any conventional or desired manner, for example as described herein-after with reference to Fig. 3, and the minimum temperature *T'* of the cylindrical wall is therefore at the meeting edges of the wall *c* and the disk *a*.

In prior rotor constructions of this general type, the major heat transfer has been by conduction through the walls of the rotor body, and heat transfer by convection currents of the air within the hollow rotor has contributed only in a minor

way to the cooling of the cylindrical surface of a rotor. The temperature gradient along a rotor of this type for a temperature difference Δt_1 between the ends of the rotor is shown by curve I of Fig. 2.

The convection currents are set up within the hollow rotor since the walls of the gas chamber are at different temperatures and the gas chamber is located in a field of force, i. e., of centrifugal force. The radial acceleration in turbine rotors may be of the order of 10^3 to 10^4 g, where g is the acceleration of gravity, and the present invention takes advantage of this high acceleration to increase the heat transfer of the conduction currents of the enclosed gas or mixtures of gases, for example air, to a high value approximately that of conduction through metal.

According to the invention, the gas mixture, air or gas g within the rotor is placed under heavy pressure to increase the heat transfer of the conduction currents. The rate of heat transfer increases with the mass, or pressure at a given temperature, of the gas or gas mixture within the hollow rotor. The term "heavy pressure" signifies pressures above atmospheric and of the order of several atmospheres and upward, but the appropriate heavy pressure value depends upon the composition of the gas or gas mixture and the cooling requirements for the particular turbine or turbine-compressor assembly. For example, when charged with air under a pressure of 100 atmospheres, and turbulent convection streams, the rate of heat transfer is twenty-one times that obtained with air under atmospheric pressure. The air layer adjacent the cool end wall a is relatively dense and heavy, as compared to the air layer adjacent the hot end wall b of the rotor, and the air layer at the cool wall a is therefore thrown outwardly by centrifugal force, as is indicated by the arrows on the lines p which show the paths of the convection currents within the rotor. In this case a temperature gradient along the rotor as shown by curve II in Fig. 2 is obtained, the temperature difference between the ends of the rotor being Δt_{II} .

The rate of heat transfer, and therefore the cooling action, may be increased still further by a suitable selection of the high pressure gas within the rotor. For example, if hydrogen is substituted for air within the rotor, the cooling action is increased two-fold.

In a turbine as illustrated in Fig. 3, a rotor 1 is provided with a plurality of rows of blades 2 and is supported, by stud shafts 3 and bearings 4, for rotation within a stationary turbine casing 5 carrying rows 6 of blades which are interleaved with the blade rows of the rotor. The rotor 1 includes end disks or plates a', a' and at least one intermediate disk b' which subdivides the space within the hollow rotor 1 into a plurality of cylindrical chambers 7, 8 of circular cross-section. Streams 9 of a cooling medium are supplied through conduits 10, 11 to flow over the disks a', a' at the inlet and outlet ends, respectively, of the turbine rotor. The chambers 7, 8 are charged with air or gas under high pressure, and the relatively dense heavy layers of air or gas at the inner faces of the disks a', a' are thrown outwardly by centrifugal force to establish convection currents along paths p. A high order of heat transfer from the intermediate disk b' to the end disks a', a' is thus established.

The detailed construction of the rotor 1 is not an essential feature of the invention and it is

to be understood that the invention may be applied to rotors of various designs and constructions which have one or more interior chambers.

The invention is of special advantage in the case of turbo-compressors of the type in which the turbine blades 12 and compressor blades 13 are carried by a single rotor body 14, as shown in Fig. 4. The rotor body is hollow at the compressor section and is filled with gas g under heavy pressure and it may be hollow or, as illustrated, may be solid at the turbine section. The gas or air is relatively cool and dense adjacent the inlet end wall a'' of the compressor section, and the gas or air is thrown outwardly along wall a'' to set flow along convection current paths p. The compressor load is of course increased somewhat by the transfer of heat from the turbine section to the compressor section, but the heat transfer is small with respect to the volume of air handled by the compressor and the increased power requirement imposed upon the turbine to facilitate the cooling of the turbine rotor is negligible.

The advantages of cooling the turbine rotors according to the invention are:

(1) The convection currents do not absorb any kinetic energy from the rotating turbine rotor, and the cooling is practically effected without introducing additional losses in the working cycle of the turbine plant.

(2) The increased cooling action affords great freedom in the design and construction of the rotor, thus affording the additional and specific advantages:

(a) low heat tensions in starting and stopping operation of the turbine,

(b) small axial moment of inertia and from this the possibility of great acceleration with variable speed turbines,

(c) freedom in the design of rotors for turbines for use on ships and aircraft,

(d) a uniform distribution of the cooling effect along the cylindrical surface of the rotor.

It is to be understood that this invention is not limited to turbines with the rotor constructions herein described and illustrated, and that various changes which may occur to those familiar with the design and construction of high temperature turbines fall within the spirit and scope of the invention as stated in the following claims.

I claim:

1. In a turbine or compressor-turbine assembly for operation by high temperature motive fluids, a rotor having a cylindrical wall carrying blades and radial walls cooperating with said cylindrical wall to form a closed interior chamber of cylindrical form, means for cooling a radial wall of said rotor, and a gas non-liquefiable at atmospheric temperatures confined within said closed chamber under super-atmospheric pressure, said gas being hydrogen.

2. In a turbine or compressor-turbine assembly for operation by high temperature motive fluids, a rotor having a cylindrical wall carrying blades and radial walls cooperating with said cylindrical wall to form a closed interior chamber of cylindrical form, means for cooling a radial wall of said rotor, and a gaseous coolant consisting of air confined within said closed chamber under a pressure of the order of 100 atmospheres.

3. A rotor for a turbine-compressor, said rotor comprising a rotor body, a series of rows of turbine blades carried by said rotor body, a series of rows of compressor blades carried by said rotor

body, the section of the rotor body carrying said compressor blades including a cylindrical wall and radial walls cooperating therewith to form a closed interior chamber of cylindrical form, means for cooling a radial wall of said chamber, and a 5 gaseous coolant consisting of air confined within said closed chamber under a pressure of the order of 100 atmospheres.

HANS BAUMANN.
